LOCK

Harry A. Barrett, Upper Darby Township,
Delaware County, Pa.

Application February 6, 1939, Serial No. 254,974

10 Claims. (Cl. 70—314)

This is a continuation in part of application for Letters Patent filed by me on November 1, 1932, Serial No. 640,587, for patent on Keyless lock, which has become Patent No. 2,145,853, dated February 7, 1939.

My invention relates to locks and it relates more particularly to permutation or combination locks mounted in doors or other sealing means.

One object of my invention is to provide a 10 permutation lock adapted to be relatively permanently mounted in a door or other sealing means.

Another object of my invention is to provide a permutation lock for use in doors or the like, which shall be so constructed as positively to dis- 15 arrange the lock tumblers when the bolt is moved, operably to require a complete re-setting of the combination after each closing of the door.

A further object of my invention is to provide 20 a permutation lock for use in doors or the like, wherein the use of springs has been eliminated so far as possible, and the component parts have been reduced to a minimum.

Another object of my invention is to produce a 25 lock which is of rugged construction and pick-proof, while at the same time inexpensive to manufacture.

A further object of my invention is to provide a 30 permutation lock which may readily be permanently mounted on locker doors or the like.

With the above and other objects in view, my invention consists of a lock housing having mov- 35 ably mounted therethrough a bolt; a plurality of tumbler disks, means for rotatably mounting said tumbler disks in said housing, registerable indentations on the peripheries of said tumblers, means in 40 pivotal connection with said bolt for abutting the periphery of at least one of said tumblers when said indentations are not in registry, and for passing into said indentations when they are in 45 registry, operably to maintain said bolt in locked condition while the tumbler indentations are out of registry, and to permit movement of said bolt to an unlocked condition when said indentations are in registry, and means for rotating said tumbler disks.

My invention also consists of a lock comprising 50 a bolt and a plurality of tumblers, permutation means for bringing said tumblers in release position, and means actuated by the motion of the bolt for bringing said tumblers out of release condition.

My invention further consists of a lock comprising 55 a bolt, a dog carried by said bolt, a plurality of indentation-bearing tumblers permula-

tively alignable, a dog-catch adapted to retain said dog in locked position when said tumblers are out of release position, and adapted to permit said dog to be withdrawn when said tumblers 5 are in release position.

My invention also consists of a lock comprising a permutation actuated tumbler and a locking member adapted to be alternately locked and released by said tumbler and means for transposing 10 said tumbler from release condition to locking condition as the locking member is moved into unlocking condition.

My invention further consists of the combination 15 of a door and a lock, said lock comprising a lock mechanism, means for supporting said mechanism, a dial, means for mounting said supporting means on one portion of said door, a bearing arm supporting said dial in another portion of said door, and operatively connecting said dial with said mechanism, and means for locking said bearing arm in place.

For the purpose of illustrating my invention, I have shown in the accompanying drawings forms thereof which are at present preferred by 25 me, since the same have been found in practice to give satisfactory and reliable results, although it is to be understood that the various instrumentalities of which my invention consists can be variously arranged and organized and that my 30 invention is not limited to the precise arrangements and organizations of the instrumentalities as herein shown and described.

Referring to the drawings in which like reference characters indicate like parts:

Figure 1 represents a front elevational view of a 35 lock mounted in a door, embodying my invention.

Figure 2 represents a side elevational view, partly broken away, of the lock and door illustrated in Figure 1.

Figure 3 represents a vertical elevational view of the lock, unmounted, and with the dial and cover plate removed, showing the inside mechanism, embodying my invention.

Figure 4 represents a sectional view taken along the line 4—4 of Figure 3.

Figure 5 represents a rear elevational view of the lock mounting, embodying my invention.

Figure 6 represents a prospective view of the 50 retaining member of the lock mounting, embodying my invention.

Figure 7 represents a perspective view of the lock cover plate embodying my invention.

Figure 8 represents a front elevational view, 55

partly broken away, of a modified construction of the lock embodying my invention adapted for use in locker doors of the latch bar type.

Figure 9 represents a sectional view taken along the line 9—9 of Figure 8.

Figure 10 is a vertical sectional view of the lock of modified construction embodying my invention.

Figure 11 represents a view similar to Figure 10, but with the locking mechanism in a released position.

Figure 12 is a sectional view taken along the line 12—12 of Figure 10.

According to my invention, I provide a lock housing 20 comprising an upper wall 21, lower wall 22, side walls 23 and 24, and rear wall 25. The upper and lower walls 21 and 22 are flanged as at 26 and 27, respectively. The wall 24 comprises a rectangular bearing 28 adapted to accommodate the lock bolt 29. A stationary shaft 30 is fixedly secured to the rear wall 25 and projects forwardly a substantial distance through the front of the housing 20. A boss 31 concentric with the shaft 30 projects forwardly from the rear wall 25.

A substantially circular tumbler disk 32 is mounted on a shaft 30 in juxtaposition to the boss 31. Substantially similar tumbler disks 33 and 34 are mounted on the shaft 30 and the tumblers 32, 33 and 34 are maintained in spaced relation to each other by spacer washers 35 and 36.

The spacer washers 35 and 36 each comprises a base member 37, anchored within the close-fitting groove 38 extending through a boss 39 which projects upwardly from the bottom wall 22. Arcuate arms 40 and 41 radiate from either side of the boss 37, said arms being of a circular curvature concentric with the shaft 30 but of an internal radius slightly less than the radius of the periphery of the tumbler disks 32, 33 and 34, and an external radius slightly greater than that of the periphery of said tumbler disks. The arcuate arms 40 and 41 preferably comprise between them a semi-circular annulus. A driving lug 42 projects forwardly from the forward face 45 of the forward tumbler disk 34 and is adapted to ride within, and be carried by the walls of, the groove or driving bearing 43 cut into the face of the rearwardly projecting bearing arm 44 of the dial 45.

A rearwardly projecting lug 46 is disposed on the rear face 47 of the forward tumbler disk 34, intermediate the shaft 30 and the spacer washer arms 40 and 41; and is adapted to contact and drive a co-radially disposed forwardly projecting driving lug (not shown) on the forward face of the intermediate tumbler disks 33 in a manner similar to that of the tumbler disks shown in my co-pending application Serial No. 640,587, filed November 1, 1932. Likewise, the tumbler disk 33 has a rearwardly projecting lug which is adapted to contact and to drive a forwardly projecting lug on the rearward tumbler disk 32. The rearward tumbler disk 32 has a rearwardly projecting lug 48 disposed close to the periphery thereof.

The bolt 29 comprises a forward face or abutment 49, a rearwardly curved camming surface 50 and a vertically disposed spring bearing wall 51. The rearward portion of the bolt 29 is fixedly secured to or preferably formed integrally with an upright arm 52. The upper portion of the arm 52 is adapted to abut against the side wall 24 when the bolt is fully extended in the locking position, and the arm 52 projects transversely in the upper portion thereof toward the opposing

side wall 23, thereby forming the upper arm 53. This upper arm 53 is spaced from the side walls 23 and 24 a total distance slightly less than the distance the bolt 29 projects out of the housing 20, and is slotted near the end thereof, opposed to the bolt end, as at 54 in a manner to receive the guide bolt 55. The slot 54 is so disposed and of such a length as to permit the bolt 29 carried by the arm 52 and 53 to be completely withdrawn into the housing 20, and to be fully extended in locking position, at will. A spring retaining pin 56 is disposed in the lower portion of the housing and has mounted thereon a coil spring 57, one end 58 of which is anchored in the boss 39, and the other end 60 of which bears against the bearing wall 51 of the bolt 29 in a manner constantly to urge said bolt outwardly.

A dog 61 is pivotally mounted on the upper arm 53 by means of the dog retaining pivot bolt 62. A spring 63 is anchored at one end in the bearing wall 51 of the bolt 29, and bears at its other end against an arm 64, which projects forwardly and downwardly from the end of the dog 61 opposed to the pivoted end thereof, operably to urge the lower end of said arm 64 against the peripheries of the tumbler disks 32, 33 and 34.

A bell crank 65 is pivoted beneath the slotted end of the upper arm 53 as at 66, and has an upper, side-grooved arm 67 and a lower, transversely extending arm 68. The slotted end of the bolt-carrying arm 53 has downwardly projecting from the lower edge thereof, a pin 69 which moves transversely across the wide groove 70 in the upper arm 67 of the bell crank 65, and is adapted alternately to abut against the sides thereof in a manner intermittently to rock said bell crank. Thus, when the bolt 29 is extended outwardly into locking position, the pin 69 traverses the groove 70 and bears against one side wall 71 thereof, operably to rock downwardly the lower transversely extended crank arm 68; and when the bolt 29 is withdrawn into unlocking position, the pin 69 bears against the opposing side wall 72 of the groove 70, operably to rock upwardly the transverse arm 68 of the bell crank 65. The transverse arm 68 extends, when in the latter position, across the path of the rearwardly projecting lug 48, and clears said path when in the former position.

Each of the tumbler disks 32, 33, and 34 has formed in the periphery thereof a notch adapted to receive the arm 64 of the dog 61, and the side wall 73 of the notch in the forwardly disposed tumbler 34 is so shaped as to engage the dog in a manner to drive the same transversely operably to transpose the bolt carrying arms 52 and 53, and the bolt 29 from a locking position to an unlocking position.

The rearwardly projecting lug 48 of the rearward tumbler disk 32 is so disposed with relation to the notch thereof, that when the arm 64 of the dog 61 is positioned within said notch, and the bolt 29 withdrawn, rocking the bell crank 65 upwardly, the transverse arm 68 thereof will be intermediate the rearwardly projecting lug 48 and said notch.

In operation, when it is desired to withdraw the bolt 29 into unlocking position, the dial 45 is rotated according to a predetermined permutation sequence operably to align the notches of the tumbler disk 32, 33 and 34 beneath the arm 64 of the dog 61, substantially in the manner described in my co-pending application for Letters Patent Serial No. 640,587, filed November 1, 1932, which has become Patent No. 2,145,853, 75

dated February 7, 1939. The arm 64 of the dog 61 is then urged into the registered notches by means of the spring 63. The dial 45 is thereafter turned toward the slotted end of the upper arm 53, bringing the sides 73 of the notch in the forward tumbler disk to bear against the arm 64 operably to withdraw the bolt 29 in the manner hereinbefore described. In the withdrawing motion of the bolt 29 and the bolt carrying arms 52 and 53, the pin 69 traverses the wide groove 70 of the bell crank 65 and bears against the side 72 thereof in a manner to rock the transverse arm 68 of the bell crank 65 into a position between the notch and the rearwardly projecting lug 48 of the rearward tumbler disk 32.

As soon as the dial 45 is released, the spring 60 urges the bolt 29 back into locking position, carrying with it the upper arm 53 and the pin 69, which retraverses the wide groove 70 of the bell crank 65, and bears against the side 71 operably to rock downwardly the transverse arm 68 of the bell crank 65 in a manner to cause said arm 68 to bear against the rearwardly projecting lug 48, locking said lug against rotation in an upward direction. The rearward tumbler 32 carrying the lug 48 is thereby prevented from being rotated by the dog 61. In the locking movement of the bolt resulting in the movement just described, the dog 61 is carried by the bolt, and would tend to carry with it the tumbler disks into the notches of which the arm 64 of the dog 61 has been disposed. This is prevented, however, by the rearward tumbler disk 32 being prevented from rotation in that direction by the bell crank arm 68 bearing against the rearward lug 48 of the tumbler disks 32. The dog arm 68 thereafter is cammed outwardly from the notch of the rearward tumbler disk 32, and freed. To facilitate this camming, the side wall 74 of the notch in the tumbler disk 32 is shaped in a manner to provide a wide angle between said wall and the base of the notch. Further rotation of the bell crank 65 as the bolt 29 approaches the limit of its outward thrust, causes the bell crank arm 68 to clear the path of the rearwardly projecting lug 48, and to free said lug for permutative motion.

The tumblers 32, 33 and 34 are now disarranged and may not be brought into unlocking registry until the predetermined sequences of dial motions has been again effected.

The bolt 29, however, is free to be withdrawn and locked by its curved surface 50 camming against the door jamb without undue motion of the bell crank, by virtue of the wide groove 70 through which the pin 69 travels before contacting the bell crank.

A cover plate 75 of the same size and configuration as the inside edge of the housing 20 defined by the walls 21, 22, 23 and 24 is disposed within said housing flush with the flanges 26 and 27 thereof. Opposed lugs 76 and 77 project from the edges 78 and 79 respectively of the cover plate 75, and register with the respective lug 45 receiving openings 80 and 81 in a manner to be held in place by the walls thereof. An opening 82 coaxial with the shaft 30 is cut through the cover plate 75 and is of a diameter sufficient to uncover the path of rotation of the driving lug 42 about the shaft 30. A forwardly extending lug 83 is struck out of the cover plate 75 at the edge of the opening 82.

The rearwardly projecting bearing arm 44 of the dial 45 passes through a circular bed plate 84 until the dial 45 abuts thereagainst, and the

outer edge of the bed plate is spun into a dial retaining groove. A hub or bearing arm 85 projects rearwardly of the bed plate 84 and is preferably formed integrally therewith. The hub 85 embraces the bearing 44 of the dial 45 in a manner to permit rotation of the bearing arm therein while uncovering the rearward portion of the bearing arm 44.

A lock retaining plate 86 is secured to the wall of the door 87 by any suitable means, such as by welding, riveting, or the like. Bolt receiving portions 88 are formed in the lock retaining plate 86 in a manner to retain the head of the bolt between the plate 86 and the door 87, and to retain the shank of the bolt in a rearwardly extending position.

The hub 85 carrying the bearing arm 44 of the dial 45 passes through suitable apertures in the door 87 and the lock retaining plate 86, and is annularly grooved as at 89 in the portion thereof immediately behind the rearward face of the lock retaining plate 86. A spring, retaining member 90 having a handle portion 91, and two side arms 92 and 93, spaced from each other a distance equal to or greater than the diameter of the groove 89, but less than the diameter of the hub 85 is passed through the groove 89 in a manner to lock the bed plate against the front face of the door 87. If desired, the handle portion 91 of the spring retaining member 90 may fit into a suitable depression in the lock retaining plate 86. The hub 85 has formed in the rearward edge thereof, a notch 94 adapted to receive the lug 83 forwardly projecting from the cover plate 75. Bolt receiving holes 95 and 96 are formed in the respective flanges 26 and 27 of the lock housing 20.

In mounting the lock on the door, the dial and bed plate assembly is positioned against the forward face of the door 87 with the hub 85 passing through the door 87, and the lock retaining plate 86. The spring retaining member is then passed through the groove 89 of the hub 85. The lock housing is then mounted on the bolts 97, rearwardly projecting through the lock retaining plate 86, with the hub groove 94 rotated into register with the lug 83 of the bed plate 75, and the dial 45 rotated until the driving bearing 43 thereof is in registry with the driving lug of the tumbler disk 34. Suitable nuts 98 are then mounted on the bolts 97 in a manner to lock the lock housing against the lock retaining plate 86.

In Figures 8-12 inclusive, I have shown a modified embodiment of my invention wherein my lock has been adapted for use on a locker of the locking bar type. Thus, there is provided a locker 100 comprising a locker housing 101, a door 102, hinged thereon at 103 and adapted to close against the door-jamb 104. A handle 105 is vertically slidably mounted on the door 102, and is secured in any suitable manner to a vertical latch bar 106 which disengageably interlocks with the door-jamb 104. A lock 107 is mounted in the door 102 in any desired manner, with the bolt 108 of the lock 107 projecting outwardly into a slot 109 which extends through the latch bar 106. The bolt 108 has downwardly extending from the inward portion thereof, a slotted member 110 which is mounted on a guide rail 111 in any suitable manner, operably to be vertically slidably thereon. A generally vertically disposed bell crank dog 112 is pivotedly mounted on the slide member 110 by means of a pivot pin 113. On the side of the upper portion of the dog 112 opposed to the bolt side thereof I provide a wall 114

portion 114 adapted to bear against the peripheries of a series of tumbler disks 116 rotatably mounted on a shaft 117. The tumbler disks 116 are operated by permutation means similar to 5 those already described with respect to the lock in the lock housing 20, and are similarly spaced by spacer washers 118. The tumbler disks 116, however, are not notched as are the tumbler disks 32, 33 and 34, but are detruncated as at 119 so 10 that when the detruncated portions 119 are in registry and in juxtaposition to the dog wall 114, said wall will be free to rock into an abutting relation thereto, whereas said wall is prevented from rocking by the periphery of the disks 116 15 when the detruncated portions 119 are not in registry.

The rearwardmost tumbler disk 116 has rearwardly projecting therefrom a lug 120 in proximity to the periphery thereof. A lug engaging arm 20 121 extends beneath the wall 113 of the dog 112 and is preferably formed integrally with said dog, said arm 121 extending toward the shaft 117 a distance sufficient to enable it to intercept the path of rotation thereabout of the rearwardly 25 projecting lug 120. The rearwardly projecting lug is so disposed on the rearwardmost tumbler disk 116 that when the detruncated portion 119 of said tumbler disks 116 is in juxtaposition to the dog wall 114, the lug 120 is disposed near the 30 lowermost portion of said detruncated portion. Thus, when the slide 110 is raised, carrying with it the dog 112, the arm 121 intercepts the lug 120 and raises it, thereby rotating the rearwardmost tumbler disk 116 operably to bring the de- 35 truncated portion 119 thereof out of registry with the detruncated portions of the remaining tumbler disks.

A pawl or dog catch 122 is pivoted beneath the tumbler disks 116, in coplanar relation to the dog 40 112 by means of the pivot pin 123. The lowermost portion 124 of the catch 122 projects toward the dog 112 in a manner to intercept the path of the lowermost portion or rocker arm 125 of said dog 112 when said dog is raised or lowered.

45 The upper side 129 of the lowermost portion 124 of the catch 122 is cammed in a manner to cause said lowermost portion 124 to rock away from the lowermost portion 125 of the dog 112, when said portion 125 intercepts the cam 129, 50 when the dog 112 is lowered. A finger 126 projects from the catch 122 above the pivot pin 123 thereof, and toward the dog 112 in a manner to be disposed immediately beneath the lug engaging arm 121 of the dog 112 when said dog is 55 in its lowermost position. The upper side 130 of the finger 126 is cammed in a manner to be rocked away from the lug-engaging arm 121, when it is intercepted by said arm when the dog 112 is lowered. The side of the catch 122 opposed to the dog side thereof is slotted as at 127 to receive a limiting stop 128 mounted in the housing of the lock 116 operably to limit the arc 60 of rotation of the dog catch 122.

The lower edge 131 of the lug engaging arm 121 65 is cammed in a manner to intercept the upper side 130 of the finger 126, and to rock said finger 126 transversely away from the dog 112 when said dog 112 is lowered. A limiting stop 128 is formed along the edge of the dog 112 immediately below 70 the camming edge 131 in a manner to abut against the finger 126 of the catch 122 when the dog 112 is in its lowermost position. The upper edge 133 of the lowermost portion or rocker arm 125 of the dog 112 is inclined in a manner to abut 75 against the lower edge 134 of the lowermost por-

tion or latch 124 of the catch 122 when said dog 112 is in its lowermost position, and when said latch 124 is rocked towards the dog 112. The portion 135 of the dog 112 intermediate the abutting wall 132 and the inclined edge 133 thereof is 5 cut away in a manner to prevent operative interference between the dog 112 and the latch 124 while the dog 112 is being lowered.

In operation, when a lifting force is applied to the handle 105, this force is transmitted through 10 the latch bar 106 to which the handle 105 is secured, and to the bolt 108 embraced by the latch bar 106. The lifting force is then transmitted through the dog 112 and the rocker arm 125 thereof. The upper edge 133 of the rocker 15 arm 125 bears against the lower edge 134 of the latch 124 in the dog catch and is prevented from being lifted. The door is therefore locked. But when the detruncated portions 119 of the tumbler disks 116 are in registry in juxtaposition to 20 the wall 114 of the dog 112 and the lifting force is applied to said dog, the rocker arm 125 of the dog 112 cams away from the latch 124 of the dog catch 122 while the opposing end of the dog 112 rocks into the space provided therefor by the de- 25 truncated portions 119 of the disks 116. The dog 112 is then free to be lifted. Further application of the lifting force of the handle 105 raises the dog 112, and while said dog is being raised, the lug-engaging arm 121 thereof intercepts the rear- 30 35 wardly projecting lug 120 peripherally disposed at the base of the detruncated portion 119 of the rearwardmost disk 116 and lifts said lug operably to disarrange the registry of the detruncated portions 119 of the tumbler disk 116. Further lifting action of the handle 105 permits the latches 136 of the latch bar 106 to clear the locking arm 137 on the door-jamb, and the door is now unlocked.

When the handle 105 is lowered, the dog 112 40 linked thereto in a manner hereinbefore described, is lowered, and in the lowering process, the wall 114 is rocked outwardly by the circular peripheries 138 of the disks 116 operably to rock inwardly the rocker arm 125. Further lowering 45 motion of the dog 112 causes the lower edge of the rocker arm 125 to intercept the upper edge 129 of the latch 124, operably to cause said upper edge 129 to cam away from said dog 112, to permit further lowering motion thereof. Continued 50 55 lowering motion of the dog causes the camming edge 131 thereof to cam against the co-acting edge 130 of the catch 122 operably to rock said catch in a reverse direction, thereby causing the latch 124 to swing into abutting relation to the inclined surface 133 of the rocker arm 125. The dog is then again locked against outward movement, and the door 102 is again locked.

It will be noted that in this modified construction of my invention, no springs are used, the 60 parts are few, and it is virtually impossible to pick the lock since the wall 114 bears tangentially against the circular peripheries 138 of the tumbler disks 116, and no motion is imparted to the dog by virtue of the receding from the peripheries 138 of the detruncated portions 119. Thus, a lock-picker would not have the feel of irregularities caused by the rotation of the tumblers to guide him in picking the lock.

I am aware that the invention may be embodied in other specific forms without departing from the spirit or essential attributes thereof, and I therefore desire the present embodiments to be considered in all respects as illustrative and not restrictive, reference being had to the ap- 70 75 80 85 90 95

pended claims rather than to the foregoing description to indicate the scope of the invention.

Having thus described my invention, what I claim as new and desire to secure by Letters Patent is:

- 5 1. In combination, a door and a lock, said lock comprising a lock housing, and lock mechanism at least a portion of which is within said housing, said mechanism comprising a locking member moveably mounted within said housing, a dog carried by said locking member, and adapted to be rocked with respect to said member; tumbler means for permitting rocking motion of said dog when said means is in release position, and for restraining rocking motion of said dog when in locking position; permutation means including a dial, to operate said tumbler, said dial being mounted in one portion of said door, said housing being mounted in another portion of said door, moveable means for transmitting motion from said dial-mounted portion to the mechanism within said housing, and means for locking said moveable means in place while permitting operative motion thereof; and means actuated by motion of said locking member for moving said tumbler from release position to locking position.
- 10 2. A lock comprising a bolt, a dog carried by said bolt, a plurality of tumblers, indentations on said tumblers, permutation means for bringing said indentations into registry in juxtaposition to said dog, spring means for urging said dog into said indentations when said indentations are in registry and in juxtaposition thereto; means for imparting motion to said dog when it is within said indentations, operably to withdraw said bolt, and means deriving motion from said bolt for bringing said tumbler indentations out of registry when said bolt is moving in another direction.
- 15 3. A lock comprising a bolt; a dog connected with said bolt, said dog comprising a wall portion and a rocker arm; a pawl latch; means on one portion of said dog to bring said pawl latch into latching relation to said rocker arm; a plurality of rotatable detruncated tumblers; permutation means for aligning the detruncated portions of said tumblers in registry to said wall operably to permit said dog to rock out of latching engagement with said pawl latch; and means deriving motion from said bolt for bringing said detruncated portions of said tumblers out of registry with said wall when said bolt is moved into unlocking position.
- 20 4. In combination, a door and a lock, said lock comprising lock mechanism, mechanism supporting means, a dial and dial retaining means, said dial being mounted on one portion of said door, said supporting means being mounted on another portion of said door, means for locking said dial retaining means in place, and means for conveying motion from said dial portion to said mechanism.
- 25 5. In combination, a door and a lock, said lock comprising a lock housing and lock mechanism at least a portion of which is within said housing, said mechanism comprising a locking member moveably mounted within said housing, a dog carried by said locking member, and adapted to be moved with respect to said member; tumbler means for permitting motion of said dog when said means is in release position, and for limiting motion of said dog when in locking position;

permutation means to operate said tumbler means; and means actuated by motion of said locking member for moving said tumbler mechanism from release position to locking position.

6. In combination, a lock comprising a lock housing and lock mechanism at least a portion of which is within said housing, said mechanism comprising a locking member carried by said housing and in moveable relation thereto, a dog connected with said locking member and adapted to be moved by motion of said member; tumbler means for permitting motion of said dog when said means is in release position, and for limiting motion of said dog when in locking position; permutation means to operate said tumbler means; and means for moving said tumbler mechanism from release position to locking position when said locking member is moved in at least one direction; said means including a member adapted alternately to be moved into operative and inoperative positions by positive motion imparted by the movement of said lock mechanism.

7. A lock comprising a locking member and permutation operated tumblers, said tumblers being adapted to be moved into a lock release position and into a locking position; a dog connected with said locking member and actuated by motion of said tumblers when they are in lock release position operably to move said locking member, means for imparting motion to said tumblers when they are in said release position, and means deriving motion from said locking member for moving said tumblers from lock release position to locking position.

8. A lock comprising a locking member, a dog connected with said locking member, a plurality of tumblers, indentations on said tumblers, permutation means for bringing said indentations into registry in juxtaposition to said dog, means for urging said dog into said indentations when said indentations are in registry and in juxtaposition thereto; means for imparting motion to said dog when it is within said indentations, operably to move said locking member in one direction, and means deriving motion from said locking member for bringing said tumbler indentations out of registry when said locking member is moved in another direction.

9. A lock comprising a locking member; a dog connected with said locking member and comprising a wall portion; a latch; means for bringing said latch into latching relation to said dog; a plurality of tumblers having wall-receiving portions; permutation means for aligning the wall-receiving portions of said tumblers in registry to said wall operably to permit said dog to move out of latching engagement with said latch, and means deriving motion from said locking member for bringing said wall-receiving portions of said tumblers out of registry with said wall.

10. A lock comprising a locking member; a dog connected with said locking member and comprising a wall portion; a latch; means for bringing said latch into latching relation to said dog; a plurality of tumblers having wall-receiving portions; permutation means for aligning the wall-receiving portions of said tumblers in registry to said wall operably to permit said dog to move out of latching engagement with said latch.
